UNITED STATES PATENT OFFICE.

OLAF WESTGAARD AND LEVI WESTGAARD, OF SEATTLE, WASHINGTON.

EYESHADE FOR AUTO DRIVERS.

Application filed February 20, 1926. Serial No. 89,617.

Our invention relates to eye shades for auto drivers and the primary objects of the invention are to provide a shade for one eye so positioned that it will eliminate the glare 5 from the headlights of passing vehicles thereby furnishing a clear vision of the road on the side where the driver is traveling. Other objects are to provide novel means for detachably installing the shade on a frame 10 whereby same may be pivotally adjusted to cut out more or less of the objectionable glare. Another object is to provide means for closing the space between the shade and face of the driver and thus eliminating any 15 leakage of light rays at this point. Still further objects are to provide a shade that is simple and durable in construction, reliable and efficient in its adaptation, and which is comparatively inexpensive to manufacture. 20

With the above and other objects in view which will appear as the description proceeds, the invention consists of the novel construction, adaptation, combination and arrangement of parts hereinafter described 25 and claimed. These objects are accomplished by devices illustrated in the accompanying drawings, wherein—

Figure 1 is a view in side elevation of the 30 shade and embodying the main features of the invention;

Fig. 2 is a view in rear elevation of the same;

Fig. 3 is a detail top plan view of the 35 shade with the flexible closure member removed; and

Fig. 4 is a view in vertical section taken substantially on a broken line 4, 4 of Fig. 3.

Referring to the drawings throughout 40 which like reference numerals designate like parts, the numeral 5 indicates a frame having the usual temple members 6, bridge 7, right rim 8 and left rim 9. As shown in the drawings the rim 9 is preferably made 45 in a semi-circular design although we do not limit ourselves to any specific form for the frame members.

The right hand rim 8 may have a narrow 50 portion 10 adjacent its connection with the temple member 6 and may widen to a flat portion 11 the rest of its length extending below the bridge 7 that is adapted to serve as a bearing for a shade member 12 as more 55 fully hereinafter set forth. It will be understood that the rims 8 and 9 are rigidly

secured to the bridge 7 and remain in a relatively fixed position over the brow of the driver.

The shade 12 is detachably mounted on the wide portion 11 of the right rim 8 by means 60 of slots 13 at its two inner corners that fit over pins 14 secured to the outer extremities of said wide portion. To install the shade member same is pressed together to a bowed 65 position and the larger portions of said slots 13 are slipped over the heads of said pins and then released when its corner portions will spring outwardly carrying the narrower 70 portions of the slots under the heads of said pins and holding the shade member in snug 75 engagement with the rim as will be readily understood.

The pins 14 being positioned on diametrically opposite sides of the rim 8, or nearly 80 so, it will be apparent that the shade member 12 may be pivotally moved on the pins with respect to said rim as indicated in dotted lines in Fig. 4 and the shade may thus be adjusted to cut out more or less 85 light as desired.

The member 12 is not adapted to be tipped to the extent of leaving its engagement with the rim 8 at any point as only a slightly tilted position is necessary for all practical purposes. In providing means for retaining said member in any tilted position we have shown a small groove 15 projecting downwardly from the shade that is adapted to engage a plurality of similar 90 grooves 16 projecting upwardly from the rim. This object may be accomplished by roughening or serrating the engaging parts in any desirable manner.

For the purpose of cutting out any rays 95 of light that might leak through between the driver's face and the shade member we have provided a strip of cloth 17 or other fabric that may be pasted or otherwise secured around the outside of the inner edge portion of the shade. Said fabrics may be provided with a slot 18 to slip over the bridge 7 so that its inner edge will completely engage the driver's face and conform 100 to the contour thereof by reason of its flexible nature.

The shade member when installed in its 105 normal position is so designed that it will assume the form of a half cone. In Fig. 2 of the drawings it will be noted that same will cover just one half the driver's vision 110

ahead, and it is so positioned on the frame 5 that the half vision covered is between 45 degrees and 225 degrees or at a slant to the right of 45 degrees from the vertical.

5 We consider this feature a very important part of our invention.

While we have described our invention with some particularity it will be understood that we intend no limitations except 10 in so far as may be imposed by the appended claims, and that such changes may be resorted to as are within its scope and spirit.

Having thus described our invention, what 15 we claim and desire to secure by Letters Patent is:—

1. A eye shade for auto drivers comprising a frame, a bridge, a shade member adapted to form a half cone in the installed position, pins secured to the frame, and said 20 shade member having slots therein arranged to engage said pins and retain the shade in such position that the axial plane defined by the cut edges of the cone is disposed at

a slant of substantially forty-five degrees to the right of the vertical. 25

2. An eye shade for auto drivers comprising a frame, a bridge, the right rim of said frame having a relatively wide portion, pins secured to the wide portion, a half cone shade member having slots therein arranged 30 to engage said pins and retain the shade member in such position that the axial plane defined by the cut edges of the cone is disposed at a slant of forty-five degrees to the right of the vertical, pivotal means for the 35 shade member, a flexible strip secured to the inner edge portion of the shade member adapted to serve as a closure for the space between the shade and the face of the wearer, and said strip having a slot adapted 40 to fit over the bridge.

In witness whereof we hereunto subscribe our names this 2nd day of February A. D. 1926.

OLAF WESTGAARD.
LEVI WESTGAARD.
